SIPHON RECORDER

Louis Chauveau, Paris, France, assignor to Societe Francaise Radio-Electrique, a corporation of France

Application August 9, 1946, Serial No. 689,603
In France January 16, 1941

Section 1, Public Law 690, August 8, 1946
Patent expires January 16, 1961

3 Claims. (Cl. 346—33)

1

The present invention relates to the construction of a Morse signal recording apparatus of the siphon recorder type which is capable of ensuring high speed communications of the order of 300 words per minute.

The invention covers more particularly certain devices and arrangements designed for obtaining this speed and for simplifying the manipulations to be effected by the operator.

One embodiment of the apparatus is given hereinafter by way of a non-limitative example; accompanying this description are drawings which show in:

Figure 1—A general arrangement of the undulator.

Figure 2—The group of control electromagnets.

Figure 3—The moving mechanism.

Figures 4 and 5—The recording block.

Figures 6 and 7—The tape-carrier spool.

Figure 8—The moving coupling.

Figure 9—A diagram of the driving motor control circuit.

The undulator essentially comprises (Figure 1) the group of control electromagnets 1, the movable system 2, the recording block 3, the tape-carrier spools 4, the ink container 5, the whole arrangement being mounted on a base 6. The tape is driven by means of the motor 7 at a speed suitable for dealing with the signals.

The group of control electromagnets (Figure 2) comprises the two stationary field coils 8 and 9 and the two moving coils 10 and 11, the signal current flowing through these latter coils which operate on an inverted T-shaped lever 17.

Each of the field coils comprises a core 12, a yoke 13, and a casing 14, these three parts being magnetic. A winding 15 is wound on the core 12, which is connected to the leads 16 and supplied with direct current.

Each of the moving coils 10 and 11 comprises a small frame of insulating material carrying a winding suitably calculated in accordance with the signals to be dealt with. The said coils are capable of vertical movement within the gap between the stationary coils.

This assembly forms a double electro-dynamic system which is adaptable to the following combinations:

The windings of the stationary coils can be coupled in series or in parallel according to the voltage of the supply system. The circuit of each of said windings may include a resistance enabling the effect of the windings on the system to be adjusted.

The windings of the moving coils may be either independent, or connected in series or in

parallel. When the signal current is in the form of a two-battery reversed current, it is fed to both coils in such a manner that one of them moves upwards when the other moves downwards, and conversely. Or again the signal current may be in the form of a one-battery reversed current, one of the coils being supplied with the operating current and the other with the inoperative current, and the directions of movement being preserved. Resistances may be connected in the circuit of each coil to enable the effect thereof to be adjusted at will. When the signal current is in the form of one-way or simple current (operative current only) it may be fed to both coils in such a manner that the directions of movement are preserved; or again it may be fed to only one coil (operative coil), the other coil (inoperative coil) in that case being supplied with a local current, the effect of which may be regulated at will by means of a suitable resistance.

These various connections and adjustments enable a choice to be made, amongst the various circuits which will be described, of one which is most suitable, taking into account the nature of the work to be done, but the connections described in the preceding paragraph are well known in the art and do not constitute a feature of the invention.

The stationary field coils 8 and 9 may each be replaced by a permanent magnet which is suitably adjusted to produce the same magnetic field; in this case, the assembly will form a double magnetic-dynamic system, the operation of which will be identical with that previously described.

The moving system (Figure 3) comprises the inverted T-shaped lever 17, the stylus holder 18 and its stylus 23, together with the adjustable stop 19, the whole arrangement being mounted on a plate 20 which is itself suitably fixed to the upper part of the stationary coils 8 and 9.

The stylus holder 18 consists of a tube 21 which passes through the cylindrical part 22, as shown in the drawing; the stylus 23 is fixed to the free end of the tube. A jaw 24 is fixed to the other end; said jaw engages the end of the control part 45 of the inverted T-shaped lever 17.

The cylindrical part 22 is extended at its upper end to form a spherical projection or nipple on to which the rubber ink feed tube 25 is fitted. The spherical projection, the cylinder and the tube are provided with suitable holes to allow the ink to flow towards the stylus.

The cylindrical part 22 is fixed to the top of a small spindle 26 carried by a frame 27, wherein the base of said spindle rests on a stool ball 28.

The balanced inverted T-shaped lever 17 can

swivel about the pivot 29 by the action of the moving coils, as shown in Figure 2; it thus moves the stylus holder about its vertical spindle 26 in such a manner that the stylus records the signal on the tape 45 as shown in Figure 3.

The stylus holder 18 is also perfectly balanced, the weights distributed relatively to the axis being the same on the stylus end as on the jaw end. The assembly thus forms a very sensitive aperiodic system, capable of a high speed of movement for a low applied power.

In apparatus of this kind, according to the speeds of reception and the preference of the operators, it is necessary to have a means of adjusting the height of the signal recorded (dimension H, Figure 3). For this purpose, the tube 21 passes through a fork member 39 mounted on a spindle 36; said spindle is rotatable in the saddle 31; a spring 32 is provided to give tension to this movement. The fork can thus be moved by hand along the tube 21 and, according to whether said fork is more or less remote from the axis of rotation 26, the amplitude of recording of the signals is more or less short.

The saddle 31 itself is secured to sliding carriage 33 which can move, in the transverse direction, on a guideway 34; this movement is controlled by the knob 35. It enables the moving system to be centred or to assist the operative or non-operative positions.

This adjustable stop assembly is particularly practical and enables the adjustment to be effected very quickly.

Different connections can be used between the moving coils and the ends of the horizontal arms of the inverted T-shaped lever.

In one embodiment shown in Figure 2, each moving coil carries a hard metal stud 36 which is adapted to strike against a hemispherical stud 37 likewise made of hard metal, said hemispherical studs being fixed to the ends of the horizontal arm. The coils are thus independent of the lever on which they act by impact.

In another embodiment (Figure 8) the above device is completed for each moving coil by a resilient connection between the lever and the coil; said connection comprises for instance a rubber strip 38 which is fixed to the coil and passes over the arm of the lever 17.

This rubber connection may be replaced by any similar mechanical device (helical or leaf spring). Great flexibility of operation is thus obtained during rapid communications.

In the apparatus in question, it is necessary to effect three operations at the time of starting, viz: placing the tape under the stylus, starting the motor and opening the ink supply cock, the three converse operations being effected when stopping.

The recording block of the present invention enables these three operations to be combined in a single operation, both when starting and when stopping. For this purpose, the block is constructed in the following manner (Figures 4 and 5).

An inverted L-shaped member 40 is adapted to slide vertically along the support 41 on which it is held by the strap members 42 and 43. A small pulley 44, over which passes the paper tape 45, is fixed to the end of the part 40.

The part 40 is moved upwardly by springs 46 acting on cross-member 46'. An adjusting screw 47 with a locking screw 48 limits the travel at will and consequently limits the pressure of the paper against the stylus.

An opening 49 of special shape is provided in the part 40. A spindle 50 is adapted to rotate in a recess provided in the support 41. Said roller is provided with a pin 51 on which is fixed the operating knob B (Figure 1).

The spindle 50 furthermore carries an eccentric pin 52 which can move in the opening 49 and return the part 40 to its lowest position.

The whole arrangement thus forms a locking means the bolt of which is formed by the part 40. By turning the knob B in one direction the lock is closed in order to make the assembly operative; by turning in the reverse direction, the assembly is made inoperative.

For the control of the ink container and of the starting switch for the motor, a hub 53 (Figure 5) is adapted to rotate about the spindle 54 fixed to the rear of the support 41.

The hub 53 carries three fork members 55, 56 and 57. The eccentric pin 52 passes through the fork 55; it follows that by operating the control knob B the hub 53, and consequently the forks, are caused to rotate in one direction or the other.

The fork 56 acts on the button of the switch 58 so as to close or open it and thus start or stop the motor driving the tape 45, said switch also controlling the supply to the stationary coils.

The fork 57 acts through the intermediary of a small crank 59 on the plug of the ink cock 60, said cock being connected, on the one hand to the ink container 5 (Figure 1) and on the other hand to the stylus holder 18 through the intermediary of the rubber tube 25.

It will thus be seen that it is only necessary to turn the control knob in one direction in order to obtain simultaneously the positioning of the paper under the stylus, the starting of the motor and the opening of the ink cock. By turning in the reverse direction the whole arrangement is made inoperative. One-knob control is thus obtained.

Owing to the speed of the communications, it is essential for it to be possible to replace quickly the paper tape which has been completely printed.

To this end, the apparatus is provided (Figures 6 and 7) with two tape carrier spools 4 and 61 located on the base in full view of the operator.

Each spool comprises a knife-shaped metal blade 62 on which is fixed a spindle 63; the inner cheek 64 of the spool and its hub are adapted to rotate loosely about said spindle on which they are held by the screw 65. The outer cheek 66 of the spool is centred on the hub of the inner cheek through the intermediary of three resilient pins 67.

It will thus be seen that the loading of a spool can be very quickly effected; it is only necessary to remove the outer cheek, place the roll of tape on the inner cheek and re-mount the outer cheek.

The support for the two spools comprises two metal parts 68 and 69 provided with grooves into which the blades 62 are adapted to fit like a knife in its sheath.

The feed of the paper (Figure 1) has been carefully designed so that the tape in use can be readily placed in position and so that the second tape 80 can be prepared for quick insertion under the stylus after the printing of the first tape has been completed. As it comes out of the spool, the tape 70 slides on the suitably rounded edge 70 of the base 6, is then guided by the intermediate rollers 71 and 72 before passing over the pulley 44 and thence between the friction drive device 73, 74 driven by the motor 7.

An apparatus of the kind in question should be

capable of receiving communications at variable speed, from manual manipulation of the order of 20 words per minute to high speed of 300 words per minute. For all this range of speeds, the length of the recording of a given word remains the same. The driving motor for the tape should therefore have a range of speed of the ratio of 1 to 15 (for instance 600-9000 revs. per minute). A direct current motor can operate in these conditions provided that an armature rheostat and a field rheostat are inserted in its circuits. In order to simplify the control, one and the same rheostat may be used for both purposes by changing the connections thereof by means of a change-over switch.

In the apparatus according to the invention, an arrangement of this kind comprising certain special and novel features (Figure 9) is used in order to simplify the manipulation by the operator.

The shunt or compound type motor comprises an armature 85 and a field winding 81 which are connected on the one hand to one pole of the source of current (-) and on the other hand and respectively to each of the ends of the resistance 82. Said resistance can be adjusted by the change-over switch 83, the contact arm 84 of which moves at will over the studs *a* and *n*.

The other pole (+) of the source, the connection of which is controlled by the switch 58 of the recording block, is connected by the reversing switch 75 either to the input end "E" or to the output end "S" of the rheostat 82.

Inspection of the diagram shows that in the first case, the resistance 82 is inserted in the circuit of the armature 85 whereas in the second case it is inserted in the circuit of the field winding 81.

An additional stud *p* is provided at the end of the change-over switch 83 in such a manner that the arm 84 can be placed either on the stud *n* only, or astride on the studs *n* and *p*.

The stud *p* is connected to the coil of an electro-magnetic relay 76; said relay controls the reversing switch 75 and is provided with a holding contact 77, the circuit of which can be broken by the push-button 78.

A connection 79 permanently connects the arm to the input end of the resistance 82.

This assembly operates as follows:

When starting, assuming that the arm 84 is on the stud *a*, the resistance 82 is completely inserted in the circuit of the armature 85, whereas the field winding 81 is directly connected to the terminals of the supply system; the motor rotates at its lowest speed.

By moving the arm in the direction of the arrow F, the value of the resistance 82 is gradually decreased, the speed of the motor increases until, when the arm reaches the stud *n*, the motor rotates at its normal speed, the armature and the field then being supplied direct from the supply system. The variation of speed is thus obtained by means of the armature rheostat.

At this instant, if it is necessary further to increase the speed, it is only necessary for the operator to push the arm astride the studs *n* and *p*; the relay 76 operates and remains operative by means of its contact 77 and the push-button 78. The + pole of the source is then connected by the reversing switch 75 to the output end S of the resistance 82. The resistance is switched into the field winding circuit. Then, by gradually moving the arm in the opposite direction to the arrow, the resistance 82 is gradually inserted in this circuit 81, and the speed of the motor increases until,

as the arm again reaches the stud *a*, the highest speed is obtained.

It will thus be seen that by moving the arm 84 in the direction of the arrow up to the extreme end position, then in the reverse direction until it is returned to the extreme starting position, the motor is made to pass through all its successive speeds of operation.

This arrangement has the following further advantages over the previously described arrangement:

When in communication, it is often necessary, after receiving a high speed message, to return very quickly to low speed in order to receive a service indication transmitted at manual speed; in this case, using the diagram of Figure 9, it is only necessary to depress the button 78 in order to make the relay 76 inoperative, the resistance portion which, at high speed, was in the field circuit is sharply switched into the armature circuit, whereby a sudden reduction of speed is produced.

On closing down, the switch 58 is opened and the relay 76 becomes inoperative; it follows that the arm 84 may be left in any position and that, when the device is used again, the motor will always start on the low speed range, thereby preventing the breakage of the tape due to starting at too high a speed.

The present description is given by way of a non-limitative indication; the various elements described may be used together or separately in the application contemplated or in all other applications of the same kind (various recorders).

In particular, the special diagram of the driving motor circuit can be used for any industrial arrangement in which it is required to obtain a wide range of speed variation of the motor with low speed starting.

The elements may be modified according to requirements; thus, for instance, the inverted T-shaped lever 17 may be eliminated, the coils 10 and 11 being laterally coupled direct to the stylus holder 10 and the stationary coils 8 and 9 being suitably placed for this arrangement.

I claim:

1. Apparatus for receiving and recording telegraphic signals comprising in combination a rod pivotable about a vertical axis, a stylus mounted at one end of the rod and a hinge connection at the other end of the rod, an actuating lever operatively connected to the hinge connection having the shape of an inverted T the upper end of the vertical branch thereof being connected to said hinge connection, electromagnet actuating means associated with said lever and responsive to the telegraphic signals, a paper strip adapted to be fed past the stylus and in contact therewith, variable speed drive means for feeding the said strip of paper, a fork engaging either side of said rod, and mechanical means operative to displace said fork longitudinally of said rod.

2. Apparatus according to claim 1 wherein the electromagnet actuating means comprises two movable cylindrical coils each displaceable in a permanent radial magnetic field.

3. Apparatus according to claim 1 wherein the variable speed driving means comprises in combination a direct current motor having a shunt field winding, an armature, and a resistance connecting one terminal of the field winding to one terminal of the armature, a series of taps connected to different points of the resistance, a brush engaging each of the taps, an inverting relay having an energizing coil connected to one of

said taps and an inverter connected on the one hand to one terminal of a source of direct current and on the other hand to both ends of the resistor, the energizing coil of the relay being series connected to a push-button switch.

LOUIS CHAUVEAU.
